William Hertzberg Inventor

By his Attorney

Martin Joachimsohn

UNITED STATES PATENT OFFICE.

WILLIAM HERTZBERG, OF BROOKLYN, NEW YORK.

MOP HOLDER.

Application filed August 13, 1925. Serial No. 50,051.

This invention relates to improvements in brushing and scrubbing implements, particularly mop heads or holders, and it is the principal object of this invention to provide a mop head with novel and improved means for holding the wire frame of the mop head to its handle sleeve with its meeting ends in intimate contact.

Another object of the invention is the provision of a mop head of simple and inexpensive construction, yet durable and efficient in operation.

A further object of the invention is the provision of a mop head providing a swivel bearing to which the mop handle is secured.

A still further object of the invention is the provision of novel and improved means for uniting the handle with its holder sleeve.

These and other objects and advantages of the invention will become more fully known as the description thereof proceeds and will then be specifically defined in the appended claims.

In the accompanying drawing, forming a material part of this disclosure:

Fig. 1 is a plan view of the mop and holder constructed according to the present invention.

Fig. 2 is a sectional detail front elevation 30 of the mop head holder, illustrating the method of holding the wire frame in the holder.

Fig. 3 is a sectional end elevation thereof.

The illustrations in the drawing show a mop head consisting of a wire frame or core 35 made of a plurality of wire strands 10 and 10^a which hold the mop material 20 and are twisted together in the manner shown, the meeting inner ends of which are held together by welding the two ends of the peculiarly 40 bent wire at a point marked 11, which lies within a tubular bearing 12 formed at the lower end of the mop holder 13, the mop holder which joins the wire frame 10 to the

mop stick 17 consists of two parts, the stem 45 13 and the cap 18. The sleeve is made from a single piece of metal pipe or tubing preferably seamless steel tubing which is formed by special dies into the shape shown. The upper end of tube 13 is provided thereby with the

50 screw thread 16 for holding the mop-stick 17. The lower or front part of the holder is formed by compressing the tube so that opposite portions of its walls form a pair of flat plates joined together along opposite sides.

55 At its lowest end this plate is bent into semi-

cylindrical shape to form one half of the bearing 12 for the wire frame 10 which holds and covers the welded joint in this frame. The second part of the mop holder consists of the cap 18 bent from a flat strip of metal having preferably double the thickness of the wall of tube 13 to form a complementary part for that portion of the mop holder lying downward of line 14. This cap is also bent into semicylindrical shape at 19 to form the 60 second half of the tubular bearing 12. The cap 18 is preferably riveted to the mop holder body 13 by an eyelet rivet 15—15^a but may be fastened thereto in any other manner for instance by welding along the edges, or by 65 bolt and nut.

A very rigid mop holder is produced by this invention as at all cross sections the material of the stem is of double thickness, this is rigidly held together in all directions which 70 feature cannot be obtained by mop heads made of sheet metal.

It is also of special advantage that the tubular part of my mop holder completely 75 encloses the lower end of the mop stick, forming a cap and thereby protects it from moisture and consequent rotting.

Furthermore it is easy to replace a worn-out mop by removing the eyelet 15 and replace the same.

While I have shown and described the preferred form of my device as an example of the many ways of practically constructing my improved mop head, it is to be understood that such changes may be made in its general 90 arrangement, and in the construction of the minor details thereof as come within the scope of the invention defined in the claims, without departure from the spirit of the invention and the principle involved.

Having thus described my invention, what I claim as new and desire to secure by Letters Patent is:

1. A mop holder consisting of a short length of normally open-ended seamless 100 metal tubing flattened out for part of its length to provide a cylindrical socket to receive a mop handle and having one of its sides flattened against the adjacent side to provide a flat plate closing the end of the socket and 105 having double the thickness of the socket wall, said socket having screw threads for engaging the mop handle, and a companion plate fastened to said flat plate, both of said plates having transverse grooves in juxtaposi- 110

tion to each other forming a cylindrical bearing for holding a mop frame rotatably supported therein.

2. A mop holder consisting of a short length of normally open-ended seamless tubing flattened out for a portion of its length to provide a flat plate of double the thickness of the tubing, the remaining portion of the tubing being cylindrical to receive the end of the mop handle and having screw threads for engaging the mop handle, the said flat plate closing one end of the cylindrical portion and

being positioned substantially in longitudinal alignment with a side wall of the said cylindrical portion, and a companion plate of double the thickness of the wall of the tubing fastened to said flat plate, both plates having grooves therein in juxtaposition to each other for holding a mop frame rotatably mounted therein.

Signed at Brooklyn, in the county of Kings and State of New York, August 10th, A. D. 1925.

WILLIAM HERTZBERG.
